ABSTRACT OF THE DISCLOSURE

An asphalt pavement cutting disc is removably attached to the scarifying blade of a grader. The cutting disc is mounted in caster wheel fashion so that it aligns automatically with the direction of grader movement, allowing the cutting action to occur smoothly along a straight line as well as on a radius or curve as required by the steering action imparted to the grader.

BACKGROUND OF THE INVENTION

Rotary cutting discs for asphalt pavement cutting, as for example in trenching or patching operations, conventionally are rigidly attached to the mold board or scarifying blade of the associated road grader or the like equipment. As a consequence, such cutting discs perform properly only when the grader is moving along a straight line or, due to the rigid connection of the cutting disc to the blade, some degree of plowing action will occur if the grader is moving along a radius.

BRIEF SUMMARY OF THE INVENTION

According to the present invention, a rotary cutting disc for asphalt pavement cutting is mounted for castering action about a vertical pivot axis so that the cutting disc may smoothly follow the contour desired even along a relatively sharp radius on the road surface, the cutting disc automatically aligning itself according to the direction of movement of the associated road grader or the like.

A slight but finite offset is established between the axis of rotation of the cutting disc and the vertical swiveling axis so that a positive cutting action occurs while at the same time achieving a nicety of alignment allowing the aforesaid sharp radius cutting action to occur without imposing undue side stresses upon the cutting disc and its mounting assembly.

BRIEF DESCRIPTION OF THE DRAWING FIGURES

FIG. 1 is a side elevational view, partly in section, illustrating the rotary cutter disc according to the present invention as attached to the mold board of a road grader or the like;

FIG. 2 is a plan view of the assembly shown in FIG. 1, and

FIG. 3 is an enlarged vertical section taken substantially along the plane of section line 3—3 in FIG. 1.

DETAILED DESCRIPTION OF THE INVENTION

With reference now more particularly to FIG. 1, a moldboard or scarifying blade 10 of a road grader or like piece of equipment is attached by conventional means to the frame or chassis of the vehicle involved and is provided on its rearward side with reinforcing plates 12 and 14 interconnected by a vertical web plate 16. Attaching ears 18 and 20 are provided on the rear face of the reinforcing plate assembly to project above and below the respective plates 12 and 14, the ears 18 and 20 being positioned adjacent to one or the other of the lateral extremes of the moldboard 10 so that a rotary pavement

2

cutting disc assembly 22, according to the present invention, is correspondingly located with respect to the scarifying blade or moldboard 10.

The assembly 22 comprises a mounting bracket 24 including a vertical plate portion 26 and a trailing generally horizontal shelf portion 28. The lower end of the vertical plate portion 26 is provided with an L-shaped jaw member 30 whereas the shelf portion 28 is provided with a jaw member 32 mounted thereon by a pivot pin 34 extending between upstanding bracket ears 36 and 38, see FIG. 2. A bolt 40 passes through the jaw 32 and threadedly engages in a suitable opening in the shelf portion 28, FIG. 1, so as to urge the jaw member 32 downwardly, whereby the two jaws 30 and 32 cooperate to clamp the ears 18 and 20 and thus securely hold the bracket assembly 24 rigidly with respect to the moldboard 10.

The shelf portion 28 is provided with an opening 42, FIG. 3, which removably receives a cylindrical housing 44 having an annular flange 46 engaging the underside of the shelf portion 28 and provided with openings in alignment with corresponding openings in the shelf portion 28 receiving bolts 48 whereby the housing is rigidly affixed to the shelf portion 28. The housing 44 is provided with a vertical bore 50 rotatably receiving a spindle 52, the upper end 54 of which is of reduced diameter and is provided with external threads for receiving locking nuts 56.

The lower end of the spindle 52 carries an inverted L-shaped arm having a horizontal portion 58 rigidly affixed to the spindle, and a vertically depending portion 60 carrying a stubshaft 62 at its lower end. A sleeve 64 is rotatably journaled on the stubshaft 62, the sleeve 64 being provided with an annular flange 66 and an extension 68 beyond the flange 66 enclosing the stubshaft 62 in its entirety and provided with an end cover plate 70 for sealing the sleeve against the entry of dirt and the like. The stubshaft 62 is provided with a retaining nut 72 preventing axial displacement of the sleeve 64 with respect to the stubshaft 62.

A rotary cutting disc 74 is provided with a bolt circle corresponding to openings in the flange 66 and suitable securing bolts 66 secure the cutting disc 74 removably on the sleeve assembly. The cutting disc 74 is provided with a sharp edge portion 77 on its periphery whereby to penetrate and cut asphalt pavement in conventional fashion.

As may be seen in FIG. 3, a thrust washer 78 is provided between the stubshaft arm portion 58 and the bottom of the housing 44 and the housing may be counterbored at its upper end to receive a further thrust washer 80 against which the locking nuts 56 lightly bear so as to retain the spindle against axial shifting with respect to housing 44 while allowing rotary motion of the spindle 52 within the housing. The housing at its upper end may include an extension portion 82 to enclose the upper end 54 of the spindle 52, and closed by a sealing plate 84 to prevent the entry of foreign material into the interior of the housing 44. Diagonal stays or reinforcing struts 84 and 86 may be provided to extend between the portions 26 and 28 of the mounting bracket assembly 24.

The arm portion 60 is inclined rearwardly at a slight angle so as to position the horizontal axis of the stubshaft 62 slightly behind the vertical axis of the spindle 52 so that whereas a major portion of the area of the cutting disc 74 lies behind the axis of the spindle 52, a minor but substantial portion of the cutting disc 74 lies forwardly of the axis of the spindle 52. In this way, a castering action is effected without sacrificing the proper operation or allowing the disc 74 to wobble with respect to the direction of movement of the vehicle to which it

is attached. At the same time, the rather mild caster action allows the cutter disc 74 smoothly to follow the contour dictated by the movement of the vehicle to which it is attached, thus allowing the cutter blade or disc 74 to follow smoothly and align with the direction of movement even on relatively sharp radius turns as, for example, in the order of 25 foot radius.

What is claimed is:

1. In combination with a grader vehicle having a generally horizontal scarifier blade, a rotary pavement cutter assembly attached to said scarifier blade, said assembly comprising,

a mounting bracket member including means for removable attachment to said scarifier blade, said bracket having a generally horizontal shelf portion trailing said blade,

a vertical housing fixed to said shelf portion, a vertically disposed spindle rotatably received in said housing,

an arm fixed to and depending from said spindle, said arm having a horizontal stubshaft offset rearwardly from the axis of said spindle,

and a cutter disc rotatably received on said stubshaft.

2. The rotary pavement cutter according to claim 1

wherein said arm trails the axis of said spindle such that, for straight line motion of the cutter disc, a substantial but minor portion of the cutter disc lies forwardly of said axis of the spindle.

3. The rotary pavement cutter according to claim 2 wherein said arm is laterally offset from said spindle and said stubshaft projects laterally of said arm, said cutter disc being contained within a plane also containing the axis of said spindle.
